UNITED STATES PATENT OFFICE.

EDMUND C. MORGAN, DECEASED, LATE OF NEW YORK, N. Y.; BY OLIVE EUGENIE MORGAN, EXECUTRIX, OF NEW YORK, N. Y.

LOADING APPARATUS.

Application filed August 13, 1923. Serial No. 656,989.

To all whom it may concern:

Be it known that EDMUND C. MORGAN, late a citizen of the United States, deceased (as by reference to the duly certified 5 copy of letters testamentary will more fully appear), had invented a new and useful Improvement in Loading Apparatus, on which United States Letters Patent is hereby being applied for by the executrix of the 10 last will and testament of the said EDMUND C. MORGAN, deceased, and the following is a specification of said improvement.

The present invention relates to loading 15 apparatus and is particularly adapted for use in connection with automatic coal mining and loading apparatus, although it may have a general application.

One of the objects of the present invention 20 is the provision of improved and efficient mechanism for tilting a mine car truck to facilitate the loading of material into the elevated end thereof.

Other objects of the invention will appear 25 hereinafter, the novel features and combinations being set forth in the appended claims.

In the accompanying drawings, Fig. 1 is 30 an elevation of a mine car with the present invention applied thereto;

Fig. 2 is a plan view of the structure shown in Fig. 1;

Fig. 3 is an elevational view of the mechanism shown in Fig. 1, but with the forward 35 end of the mine car in elevated position;

Fig. 4 is an end elevation of the mine car illustrating the addition of a superposed container; and

Fig. 5 is an enlarged elevation of the 40 elevating mechanism applied to the structure shown in Fig. 4.

Referring to Fig. 1, it will be seen that the truck-frame 6 is mounted on wheels 7 which are adapted to travel on a mine track 8.

45 Mounted on the truck-frame 6 is the car body 9 provided with vertical longitudinal spaced-apart walls 10 and the rear transverse end wall 12. By means of the usual coupling 13 the mine car may be connected to others or to a locomotive.

As shown in Fig. 2, the truck is mounted on four wheels each of which has a brake shoe 14 applied thereto. At the sides of the truck-frame lever mechanism, illustrated 50 at 15 and 16 in Fig. 2, may be used for re-

leasing and applying the brake shoes to the wheels 7. To the lever mechanism 15 is connected a rock shaft 17 and in a similar manner to the lever mechanism 16 is connected a rock shaft 18. Bell crank levers 60 19 and 20 are respectively connected to the rock shafts 17 and 18 and to the lever mechanisms 15 and 16. The bell crank levers 19 and 20 are extended rearwardly, as shown in Fig. 2, and their ends are connected by the operating cross-piece 21. By means of a latch device 22 at the rear central portion of the mine car, back of the wall 12, the cross-piece 21 may be held in elevated position so as to hold the brake 70 shoes 14 released from the wheels 7.

In the operation of combined mining and loading machines it would be desirable to lay the track 8 up to a position near the mine wall, leaving only sufficient room intervening for the proper operation of the mining and loading machine. As the mining and loading proceeds the machine is moved forward, step-by-step, beyond the forward end of the mine track. It would 75 not always be practicable to add sections to the forward end of the mine track until after the mining and loading machine had reached a position considerably in advance of the forward end of the mine track. It 80 is, therefore, desirable to maintain continual communication between the delivery end of the mining and loading machine, and the receiving end of the mine car. Provision is therefore made, as shown in the accompanying drawings, for lifting the forward wheels of the truck and relying upon the rear wheels to direct the truck along the forward end of the mine track, while the forward portion of the mine car is extended 85 considerably beyond the forward end of the mine track while being supported in position to be readily moved back on to the mine track when the mine car is loaded.

At the right-hand end of Fig. 1 an extension from the frame-work of the mining and loading machine is represented at 23. Mounted on this frame 23 is an operating lever 24 pivoted at 25 so as to move or oscillate on a horizontal axis. The lever 24 100 is provided with a lower arm 26 which has a slot 27 for receiving the pin 28 on the arm 29 of a bell crank lever pivoted at 30. It should be noted that there may be two 105 rock shafts 25 and 30 immediately above 110

one another, or spaced apart as shown in Fig. 1. The plan view in Fig. 2 shows the upper rock shaft 25 which carries the spaced apart levers 31 and 32. These levers are 5 therefore rigidly connected to the operating lever 24 and also to the lower arm 26.

Between the forward ends of the truck-frame 6 and the vertical sides 10 of the car are laterally extending rods or pins 33 10 and 34. Engaging these pins are latch-levers 35 and 36, respectively. These levers 35 and 36 are respectively pivoted at their lower ends, as illustrated at 37 in Fig. 1, to lateral arms 38 and 15 39 which are pivoted, as illustrated at 40 in Fig. 1, to the sides of the car body, spaced back from the forward end of the car and near the front wheels, but in front thereof.

20 The arms 38 and 39 are connected at their forward ends by the cross-piece 41 which, at its center, carries the coupling mechanism comprising the spaced-apart jaws 42, 42 and the coupling pin 43. As shown at 44 in Fig. 25 2, the slot between the jaws 42 is of sufficient width to receive the ends of the arms 45 and 46, which are connected rigidly with the arm 29 pivoted at 30 directly below the shaft 25.

30 The cross-piece 41 also carries the door 47 for the forward end of the car body. When the parts are in the position shown in Fig. 1 the door 47 is closed and held closed by the latches 35 and 36 engaging the pins 33 and 34. The latches 35 and 36 are yieldable rearwardly, since each is provided, as shown in Fig. 1, with a pin 48 which engages a spring 49 in a holder 50 attached to the arm 38. A similar spring-pressed 35 40 or yielding device is shown at the other side of the car body at 52, Fig. 2.

The latches 35 and 36 are also provided with laterally extending webs 53 and 54 in position to be engaged by the rear ends of 45 the levers 31 and 32, as shown in Fig. 2. Assuming the mining and loading machine to be located in advance of the mine track 8, so that the frame extension 23 occupies the position shown in Fig. 1, the mine car 50 may be moved to the position shown in Fig. 1 where the door 47 still remains closed. The momentum of the car may be relied upon to move the pins 33 and 34 into the 55 arcuate recesses between the jaws at the rear end of the levers 31 and 32; or, when the car reaches the position shown in Fig. 1, the lever 24 may be moved forward sufficiently to move the jaw 55 of lever 31 and the jaw 56 of lever 32 under the pins 33 and 34, respectively. When the jaws 55 and 56 are moved under the pins 33 and 34 they 60 respectively engage the webs 53 and 54 to release the latches 35 and 36 against the action of the resilient or yielding devices 65 51 and 52. After the jaws 55 and 56 have

released the latches 35 and 36 and moved under the pins 33 and 34 the lever 24 may be pushed forward to cause the arms 31 and 32 to lift the forward end of the truck so that the forward wheels 7 will be disconnected entirely from the mine track, whereupon the truck will be supported by the rear wheels and by the arms 31 and 32 mounted on the frame 23. Therefore, as the mining and loading machine is moved 70 forward step-by-step, together with the frame 23, the mine car may be moved so that the rear wheels will move to a position close to the extreme forward end of the track before any additional section need be 75 80 added to the mine car.

At the same time that the forward end of the truck is elevated to the position shown in Fig. 3 the spaced-apart arms 45 and 46 open the door 47 by reason of being extended into the slot 44 between the coupling jaws 42, 42. The door 47 is thus moved down positively because when the lever 24 is moved forward the pin and slot connection at 28 will rock the shaft 30 to move the 85 arms 45 and 46 down. So long as the forward end of the mine car is held elevated the door 47 is held down in open position. Therefore, the delivering conveyor of the mining and loading machine may be directed 90 into the forward open end of the mine car and as the coal is delivered to this mine car its movement toward the rear end thereof is facilitated by reason of the tilting of the mine car. 95 100

When the latches 35 and 36 are released they engage stops in front of them on the arms 38 and 39. This is illustrated at 57 in Figs. 1 and 3. These stops hold the latches 35 and 36 in position to permit their upper forward inclined faces to engage the pins 33 and 34 when the frame 23 is moved back toward the mine track sufficiently to permit the forward wheels to re-engage the mine track. When the forward end of the mine car is let down by rearward movement of the lever 24, by power mechanism or otherwise, the arms 45 and 46 will act automatically to positively lift the door 47 into 105 position to close the forward end of the mine car. Then as the mine car, which has been loaded, is hauled away the pins 33 and 34 will ride out of the jaws 55 and 56 and as soon as this occurs the latches 35 and 36 will snap into place over the pins 33 and 34 to hold the door 47 in closed position. It will thus be seen that by means of a single lever 24 the forward end of the mine car may be lifted and lowered and simultaneously the door 47 may be operated so as to move to open position when the forward end of the car is elevated and so as to move to closed position when the forward end of the mine car is lowered to the mine track level. The brake mechanism may be 110 115 120 125 130

operated and released whenever desired. For instance, after the mine car has been moved forward sufficiently to cause the pins 33 and 34 to rest in the arcuate recesses 5 of the jaws 55 and 56, the brakes may be applied and held applied while the forward end of the mine car is being elevated and the door 47 opened. But after the forward end of the mine car has been elevated the 10 brakes may be released when the mining and loading machine is to be moved forward another step so that the jaws 55 and 56 will exert a pull on the mine car at the pins 33 and 34 to move the mine car forward to another position, after which the brakes may again be applied. If desired, the brakes may also be held applied by the weight of the levers 19 and 20 and the cross-piece 21 while the forward end of the car is being lowered 15 to the position shown in Fig. 1.

In the operation of mining and loading machines in coal mining, bands of foreign material may be encountered in which event it would be desirable to load the foreign 20 material separately from the coal. The mine car may be provided with an upper compartment 58 for this purpose, this compartment being attached, as shown at 59 in Figs. 4 and 5, on top of the lower compartment 9, 25 but entirely separated therefrom by being provided with the bottom 73 shown in Fig. 5. The upper edge of the door 47 may be provided with hinged members 60 and 61 to receive the hinged members 62 and 63 on the 30 bottom of the door 64 which is adapted to fit between the wings 74, 74', as shown in Fig. 4. A lever 65 may rotate a disc 66 pivoted to the door 64 and connected to rods 67 and 68 which slide through brackets 35 69 and 70 in position to fit into perforated lugs 71 and 72. In this manner the door 64 may be released by the lever 65 and swung to open position on its hinges. After the upper compartment has been loaded with 40 foreign material the door 64 may be closed and locked.

It should be particularly noted that the use of the upper compartment for foreign material will not interfere with the door-operating mechanism for the lower compartment. The door 64 may be swung forwardly on hinge 60, shown in Fig. 3, whereupon the forward end of the mine car, including both compartments, may be tilted upwardly, 45 while the doors 47 and 64 occupy the positions shown in Fig. 5. After this has been done the coal may be loaded into the lower compartment and the foreign material into the upper compartment. It will also be seen that the two compartments may be employed 50 for receiving blocks of coal of different sizes. For instance, the large blocks of coal may be directed into the lower compartment and cuttings and slack directed into the upper compartment.

Obviously, those skilled in the art may make various changes in the details and arrangement of parts without departing from the spirit and scope of the invention, as defined by the claims hereto appended, and it 70 is therefore desired not to be restricted to the precise construction herein disclosed.

Having thus fully described and shown an embodiment of the invention, what is desired to be secured by Letters Patent of the 75 United States is:

1. In loading apparatus, the combination with a mine car adapted to travel on a mine track, of a door for one end of said car, spaced-apart arms carrying said door and 80 pivotally connected to the mine car rearwardly of its front end, and releasable latch mechanism for holding the door in its upper closed position.

2. In loading apparatus, the combination with a mine car, of an upright door for one end thereof, means for supporting said door on pivots rearwardly of the front end of said car, and means for operating said door by swinging the same downwardly on said 85 pivots to leave the space above the adjacent end of the car free and unobstructed.

3. In loading apparatus, the combination with a mine car, of a door for one end thereof, a pair of spaced-apart arms for carrying said door and pivoted to the sides of the car to permit said door to swing down to open position, pins extending laterally from the door end of the car, and a pair of automatic spring-pressed latches adapted to operate with said pins for holding said door in its upper closed position.

4. In loading apparatus, the combination with a mine car, of an upright door at one end thereof, means for carrying said door, mechanism for holding said door in close position, and means on said holding mechanism adapted to receive pressure for releasing such holding mechanism to permit the door to open downwardly by gravity.

5. In loading apparatus, the combination with a mine car having a door at one end thereof, of mechanism for supporting and holding said door closed in upright position, and means adapted to engage the holding mechanism to release the said door and move the same down to open position.

6. In loading apparatus, the combination with a mine car having a door at one end thereof, mechanism for supporting said door to swing down to open position, and means for elevating one end of said car into position to receive material and operating said supporting mechanism to swing the door down to open position.

7. In loading apparatus, the combination with a mine car having a door at one end thereof, means for supporting said door for movement to open and closed positions, and mechanism adapted to tilt upwardly the 130

- door end of the mine car and to operate said supporting means to effect the opening of the door.
8. In loading apparatus, the combination with a mine car having a door at one end thereof, of means for supporting said door for movement to open and closed positions, and mechanism for simultaneously opening said door and tilting the mine car into position for receiving material thereinto.
9. In loading apparatus, the combination with a mine car, of a door at one end thereof, means for supporting said door for movement to open and closed positions, and interconnecting levers operable from a single source of power to positively elevate the door end of the car and to positively move said supporting means to effect the opening of said door.
10. In loading apparatus, the combination with a mine car, of a door at one end thereof, means for supporting said door to swing to open and closed positions, a cross-piece connected to said door and having a horizontal slot therein, and means adapted to extend into said slot to positively swing said supporting means to open and close the said door.
11. In loading apparatus, the combination with a mine car, of a door at one end thereof, a cross-piece connected to said door, a coupler mounted on said cross-piece and having spaced-apart jaws, a pair of arms pivoted rearwardly at the front end of the car and carrying said door, said cross-piece and said coupler, and mechanism adapted to project into said coupler between the jaws thereof to open or close said door.
12. In loading apparatus, the combination with a mine car, of a door therefor, latch mechanism for holding said door in closed position and comprising a latch-pin on the car, and mechanism for engaging the latch-pin, after releasing the latch mechanism, to elevate one end of the car and to permit said door to open.
13. In loading apparatus, the combination with a mine car, of a door for one end thereof, a pair of spaced-apart supporting arms for carrying said door, said arms being pivoted to the car rearwardly of the front end thereof, a pair of spring-pressed latch devices comprising pivoted levers and lateral extensions from the car, and means for engaging the latch levers to release the same and also engage said lateral extensions to tilt the mine car.
14. In loading apparatus, the combination with a mine car, of a swinging door for one end thereof, mechanism for holding the door in closed position and comprising pins extending from the car, and means for releasing said holding mechanism and engaging said pins to tilt upwardly the door end of the mine car.
15. In loading apparatus, the combination with a mine car, of a door therefor, means for supporting said door for movement to open and closed positions, and mechanism for simultaneously tilting upwardly the door-end of said car and opening said door.
16. In loading apparatus, the combination with a mine car, of a door connected thereto for swinging movement up and down to open and closed positions, and mechanism operating to either tilt the car upwardly and simultaneously open the door or to tilt the car downwardly and simultaneously close the door.
17. In loading apparatus, the combination with a mine car, of a door for one end thereof, means for supporting said door to swing up and down to closed and open positions, and mechanism operable to either tilt the door end of the car upwardly, while the door is being swung downwardly to open position, or to tilt the door-end of the car downwardly, while the door is being swung upwardly to closed position.
18. In loading apparatus, the combination with a support, of means mounted thereon in position to be engaged by a mine car so that the latter may be tilted upwardly, and door-operating mechanism associated with said tilting means.
19. In loading apparatus, the combination with a support, of means mounted thereon for tilting one end of a car upwardly into position for receiving material thereinto, and door-operating mechanism associated with said tilting means.
20. In loading apparatus, the combination with a support, of a rock-shaft mounted on said support, a pair of spaced-apart arms having jaws adapted to receive extensions from a mine car, a depending arm rigidly connected to said rock-shaft, an additional rock-shaft, a bell-crank lever secured to said additional rock-shaft in position to engage a door of a mine car to open such door, a pin-and-slot connection between said depending arm and said bell-crank lever, and means for rotating said rock-shafts to operate said arms and said levers.
21. In loading apparatus, the combination with a support, of a pair of spaced-apart arms pivoted to said support, a depending arm connected to said spaced-apart arm to move therewith, a bell-crank lever pivotally connected to said support, an operating connection between said depending arm and said bell-crank lever, jaws at the outer ends of said spaced-apart arms in position to receive extensions from a mine car, and an operating lever for swinging upwardly said spaced-apart arms when said jaws engage such extensions to tilt upwardly the mine car, while said bell-crank lever engages a door of the mine car to open such door.
22. In loading apparatus, the combina-

- tion with a support, of a system of bell-crank levers mounted on said support comprising car-elevating arms and door-operating means, a mine car having a door at 5 one end, means comprising latch-levers and pins for holding the door closed, extensions on said latch levers in position to be engaged by said car-elevating arms to release the levers and cause said car-elevating arms 10 to engage said pins, and means on said door adapted to be engaged by the door-operating means to move the door to open position when the car is elevated and to move the door to closed position when the car is lowered. 15
23. In loading apparatus, the combination with a mine car having a longitudinal channel closed at one end and open at the other end, of a door for the open end, and 20 mechanism for tilting upwardly the open end of the car and also opening said door to place the mine car in position to receive coal from the mining and loading machine.
24. In loading apparatus, the combination 25 with a mine car having superposed separate longitudinal channels, a double folding door for the forward end of the car, manually operated mechanism for releasing the upper door, and means for tilting both 30 channels upwardly while opening the folded door.
25. In loading apparatus, the combination with a mine car adapted to travel on a mine track, of a portable supporting frame in 35 advance of the mine track, and means for tilting the car and maintaining the same connected to said support.
26. In loading apparatus, the combination with a support, of a rock shaft mounted 40 thereon, a pair of spaced arms secured to said rock shaft and extending rearwardly from said support, a pair of receiving jaws one on each of said arms in position to engage lateral projections on a mine car, and 45 means for operating said rock shaft to lift said arms to elevate the car to facilitate loading material thereinto.
27. In loading apparatus, the combination with a support, of elevating mechanism
- mounted thereon and adapted to be connected to a mine car, and means for operating said elevating mechanism to elevate one end of a mine car to facilitate loading material thereinto. 50
28. In loading apparatus, the combination with a support adapted to be located in advance of a mine track, of supporting and hauling mechanism mounted on said support and adapted to be connected to a mine car traveling on such mine track, and means for operating said supporting and hauling mechanism to connect the same to a mine car and maintain such connection while the said support is advanced and the mine car extends beyond the forward end of the mine track. 60
29. In loading apparatus, the combination with a mine car adapted to travel in advance of a mine track, of a frame of a loading machine in advance of the mine track, supporting and hauling mechanism between said frame and the adjacent end of the mine car, and means for operating said supporting and hauling mechanism to connect said frame to said mine car in a predetermined relation and maintaining such relation as the loading machine advances and the mine car moves partially beyond the forward end of said mine track. 70
30. In loading apparatus, the combination with a mine car adapted to travel on a mine track, of a frame of a loading machine adapted to be moved in advance of said mine track, supporting, hauling and elevating mechanism between said frame and one 80 end of said mine car, and means for operating said mechanism to elevate said end of the mine car and support the same for haulage with said frame as the latter is advanced and said mine car extends partially 85 beyond the forward end of said mine track. 90

Signed at New York, in the county and State of New York, this 31st day of July, 1923.

OLIVE EUGENIE MORGAN,
*Executrix of Estate of Edmund C. Morgan,
Deceased.*
